UNITED STATES PATENT OFFICE.

GEORGE F. BLASIER, OF NORTH TONAWANDA, NEW YORK, ASSIGNOR TO BUFFALO BOLT COMPANY, OF BUFFALO, NEW YORK, A CORPORATION OF NEW YORK.

MACHINE FOR SQUARE-TRIMMING METAL ARTICLES.

1,277,367.

Specification of Letters Patent. Patented Sept. 3, 1918.

Application filed April 25, 1917. Serial No. 164,580.

To all whom it may concern:

Be it known that I, GEORGE F. BLASIER, a citizen of the United States, and resident of North Tonawanda, in the county of Niagara and State of New York, have invented certain new and useful Improvements in Machines for Square-Trimming Metal Articles, of which the following is a specification.

My present invention is embodied in a machine for trimming off the circular flash, or thin lateral fin of metal which is found at the base of the squared heads of bolts as turned out by automatic bolt forging machines; and although my invention is obviously applicable to other machines for specifically different purposes, I will describe it in connection with the use for which it was primarily intended.

It is the common practice to do this trimming by passing the bolt heads between rotary trimmers, which may be two parallel pairs of rotary shears spaced apart a distance just equal to the width of the squared surfaces of the head so that the excess metal is trimmed off flush with the squared surfaces on two opposite sides of the head of the nut. The portions of the flash remaining on the other two sides of the head are removed in the same way by the same or a similar set of rotary trimmers.

My present machine comprises two successive sets of the above described parallel pairs of rotary shears, combined with a feeding guide for presenting the bolt heads squarely to the first set for trimming the flash from two sides, an intermediate guideway leading to the second set of shears and interposed in said guideway, a turning mechanism whereby the half-trimmed bolts are given a quarter turn and are then presented squarely to the second set of shears for trimming the flash from the remaining sides.

The rotary trimmers rotate in the direction of movement of the bolts and are arranged so that their trimming engagement with the successive bolts operates to feed them forcibly forward. Thus the first set of rotary shears operates to push a continuous stream of bolts through the guideway to the second set of shears. The forward pressure transmitted through the stream of bolts is utilized as a source of power for operating the mechanism for separating the bolts and giving them the quarter turn

necessary for presentation of the untrimmed flashes to the second set of shears. By arranging the guides leading to the first set of shears at a fairly steep incline, weight of the bolts may be utilized for yieldingly pressing a continuous supply of the bolts to the first set of shears. This results in a machine in which a continuous feeding, separating and turning of the bolts is automatically maintained with only the shears as the source of power and only the stream of bolts as the means for applying the power for both purposes. The operation is automatically self-regulating as to speed and it is automatically self-stopping in case of sticking or jamming of any one of the bolts anywhere in the guideway or turning mechanism.

The turning mechanism comprises two star wheels provided with suitable projections and arranged one in advance of the other in operative relation to the guideway for successive engagement with the bolts passing therein. The one first engaged by the bolts feeds them forward at approximately the rate of movement of the whole train whereas the second one feeds them forward at a considerably faster rate thereby spacing apart each bolt from the one which precedes it, so that the corners and uncut portions of the flash are freed so as to permit of the turning operation. This is accomplished by arranging an abrupt deflection in one of the two lateral guides which engage the square faces of the bolt heads and correspondingly relieving the other lateral guide so that there is room for the bolt head to turn about said obstruction as a pivot. The forward feeding of the bolt by the star wheel through this portion of the guideway gives it the required quarter turn, immediately upon the completion of which, the star wheel advances it into a portion of the guideway where the lateral guides are again parallel and prevent further turning of the squared head.

The automatic operation of the star wheels at the speeds required for successively accelerating the feed of each bolt so as to separate it from its predecessor, requires that the second star wheel have a higher peripheral speed than the first and preferably they are geared together so that the difference in the rate of speed and the resulting

amount of separation of the bolts will be constant. The preferred way is to provide the same number of bolt engaging projections on both star wheels and gear them together so that they will rotate at the same angular speed, but have the diameter of the second wheel considerably greater than that of the first wheel so that its peripheral velocity and the resulting speed of feed will be higher than that of the first. Thus arranged, the first star wheel will be rotated by the pressure of the stream of bolts forced forward to it by the first set of shears and whatever its speed, the second star wheel which is geared thereto will be driven at a higher peripheral velocity, thus carrying forward at increased speed, each bolt as delivered to it by the first star wheel.

It is simpler to have the star wheels engage the shanks of the bolts rather than the heads. The heads are square and are crowded close together by the feeding pressure from the rear, whereas the shanks are cylindrical and are spaced apart by the heads so that they are well adapted both for initial engagement and for smooth sliding and rolling contact with the star wheel projections.

The details of my invention will be more readily understood from the following detailed description of a desirable embodiment of my invention illustrated in the accompanying drawings, in which—

Figure 1 is a top plan view; Fig. 2 is a vertical longitudinal section; Fig. 3 is a vertical section of the bolt turning mechanism taken on the line 3—3, Fig. 1;

Figs. 4 and 5 are respective side and plan views of the bolts before trimming; Fig. 6 is a plan view of the bolt trimmed on two sides only; and

Fig. 7 is a plan view of the bolt trimmed on all four sides.

By reference to the drawings, particularly Figs. 4 to 7, it will be seen that the bolts to be trimmed comprise the cylindrical shank or barrel *a*, the square head *b*, and at the base of the head, the circular flash *c*, *c*, *d*, *d*. Figs. 4 and 5 show these parts in side elevation and plan while Fig. 6 shows the head after the portions of the flash *c*, *c* have been trimmed off in the first set of trimmers and the portions *d*, *d* remaining and Fig. 7 shows the completely trimmed bolt head after the portions *d*, *d* have been removed by the second set of trimmers.

The rotary trimmers are shown as pairs of rotary shears which are arranged in sets, the pairs 1 and 2 being the set at the entrance end of the machine and the pairs 3 and 4 being the set at the exit end of the machine. The pairs 1 and 2 are preferably opposite and parallel and rotated at the same speed so that the lateral component of the pinch of the two pairs of shears will

be equal and opposite, and both sides of the bolt head will be fed forward at the same speed.

The shearing plates 5 and 6 of each pair of shears have their shearing edges overlapped substantially in the plane of the squared surface of the bolt. The upper shear plates 5 preferably extend to that plane from the outside and the lower shear plates 6 from the inside so that the faces of the plates 6 form guides for the bolt shanks while their peripheries form feeding supports for the solid part of the bolt head both before and after the flash has been trimmed off. The diameter of the shear plates is relatively large and their overlap relatively slight and hence the shearing edges converge at a small angle which causes them to nip the flashes and feed them along as fast as they come within range.

The details of construction, relative arrangement, adjustment and positive driving of rotary shears for this class of heavy metal work are not shown in the drawings because they are all well known in the art and, so far as concerns disclosure of my present invention, it need only be stated that their locations and relative arrangements are as above described and that they are all positively driven at the same speed by suitable power in the direction indicated by the arrows on Fig. 2.

The guideway comprises a two part bed-plate comprising the members 7, 8 spaced apart to form a slot 9. The bolts hang by 100 their heads from 7 and 8 with their shanks projecting through the slot 9. The lateral guide plates 10, 11 are spaced from each other a distance slightly greater than the width of the squared portion of the head of 105 the bolt; also from the bottom guides 7 and 8, a distance sufficient to permit free sliding of the circular flashes on the bolt heads even when overlapped as shown in the drawings.

The mechanism for separating and turning the bolts in the portion of the guideway between the two sets of shears comprises the small star wheel 12 and the large star wheel 13, each with the same number of bolt engaging recesses, mounted on parallel vertical 115 shafts 14, 15. These star wheels engage the barrel of the bolt only. The shafts 14, 15 are of sufficient length to allow for the longest bolt to be trimmed and at their lower ends are provided with meshing gears 16, 17 having the same number of teeth, so that the star wheels rotate at the same angular speed. The bolt engaging recesses 18 on star wheel 12 and 19 on star wheel 13 are equal in number and come into registering relation for the feeding of the bolt shanks from 12 to 13. The periphery of the larger star wheel 13 however, is greater than the periphery of star wheel 12 and hence bolts will be carried forward at higher speed as soon 130

as they are delivered from the smaller wheel to the larger one.

At a point opposite the star wheel 13 the lateral guide 11 is slightly offset as at 20 and notched as at 21, while the lateral guide on the side nearest the star wheel is correspondingly cut away to afford room for the turning of the bolt around the offset 20. The shank of the bolt is of course guided laterally by the slot 9 but as an additional guiding means for steadyng the head of the bolt during the turning movement, I provide a dog 22 pivoted at 23 and provided with a depending presser-foot 24 adapted to contact laterally with the bolt heads. The dog is yieldingly pressed into contact with the bolt heads in the guideway by a spring 25 spiraled about the bolt 26 and having one free end confined by a pin 27 and the other engaging a pin 28 on the dog. The play of the dog is limited by a bolt 25 in slot 29. A fixed top guide 30 for limiting possible upward movement of the heads of the bolts is arranged over the portion of the guideway adjacent the turning mechanism.

In the above device, the inclined section of the guide is kept supplied with a continuous stream of untrimmed bolts, held square by the lateral guides 10, 11 and pressed forward by gravity toward the first set of trimming shears 1, 2. As fast as their flashes come within reach, they are nipped by the shears, trimmed on two sides and positively forced forward. This pushes the bolt against the flash of the next bolt ahead of it. This pressure transmitted forward through the train of bolts, pushes the foremost bolt into one of the recesses 18 of the small star wheel 12 thereby forcing it to revolve. This motion transmitted through the shaft 14, gears 16, 17 and shaft 15 drives the larger star wheel 13 at the same angular speed. The recesses 19 in the large star wheel 13 register with the recesses in the smaller wheel so as to engage the shank of the bolt just as it is leaving the recess of the smaller wheel. The peripheral speed of the large wheel being greater carries the bolt forward out of engagement with the following bolt which is still held in the smaller star wheel 12. The action of the rear face of the recess 19 on the round body of the bolt while moving it forward in the guideway tends to revolve it and to crowd it against and along the opposite side of the guideway where the obstruction 20 and notch 21 acting as a turning fulcrum, cause the bolt to make a quarter turn. Thereupon, the square head of the bolt passes between the parallel portion of the side guides 10, 11, which guide the bolt heads squarely to the second set of trimming shears. The bolts are successively forced into this section of the guideway by the star wheel 13 so that a continuous stream of them is forced forward at the same rate as the

portion of the stream between the first set of shears and the star wheel 12.

The action of turning is limited only by the speed at which the bolts can be put through the first set of shears, and so by controlling this feeding speed, the bolts can pass through in one continuous stream at whatever rate is permitted by the capacity of the shears.

Jamming of a bolt anywhere in the machine will operate automatically to stop the entire train of bolts, since the resulting back pressure will be transmitted to the bolts in the first set of trimming shears and will be sufficient to overcome the feeding power of the shears and hold the bolts stationary while the shears rotate idly.

While I have described with great particularity a desirable embodiment of my invention, it will be obvious that various changes, modifications and substitutions of parts as well as changes in the locations and relative arrangement of parts may be made without departing from the spirit of my invention, as defined by the appended claims.

I claim:

1. In a machine for trimming the parallel sides of square headed bolts, a guideway having centrally slotted bottom guides for supporting the bolts by the heads with their bodies depending through the slot and lateral guides adapted to engage parallel sides of the head, and successive sets of rotary trimmers along said guideway arranged in pairs so as to operate simultaneously on opposite sides of successive bolts, and rotated in a direction to force a continuous stream of the bolts along said guideway by pressure from the rear, in combination with means between said sets of trimmers for giving said bolts a quarter turn about their longitudinal axes, said means comprising an offset or obstruction formed in one of the lateral guides, a corresponding cut away portion in the opposite lateral guide, a star wheel for engaging each bolt and forcing it forward past said offset or obstruction with one corner of the squared head in turning engagement therewith and means for driving said star wheel at a peripheral speed higher than the speed at which said stream of bolts is normally forced along the guideway.

2. In a machine for trimming the parallel sides of square headed bolts, a guideway having centrally slotted bottom guides for supporting the bolts by the heads with their bodies depending through the slot and lateral guides adapted to engage parallel sides of the head, and successive sets of rotary trimmers along said guideway arranged in pairs so as to operate simultaneously on opposite sides of successive bolts, and rotated in a direction to force a continuous stream of the bolts along said guideway by pressure

- 4
- from the rear, in combination with means between said sets of trimmers for giving said bolts a quarter turn about their longitudinal axes, said means comprising an offset or 5 obstruction formed in one of the lateral guides, a corresponding cut away portion in the opposite lateral guide, a star wheel for engaging each bolt and forcing it forward past said offset or obstruction with one corner of the squared head in turning engagement therewith and means for driving said star wheel at a peripheral speed higher than the speed at which said stream of articles is normally forced along the guideway, said 10 means comprising a star wheel projecting into the path of and actuated by the moving stream of bolts and a driving connection therefrom to said first mentioned star wheel.
- 15 3. In a mechanism for turning articles having parallel sided heads and bodies of less diameter than the heads, a guideway comprising base guides adapted to engage the under sides of the heads of the articles with the bodies thereof depending between them and lateral guides for engaging parallel sides for the heads of the articles, means for feeding a continuous stream of the articles along said guideway by pressure from the rear, in combination with means 20 for turning said articles, comprising an offset or obstruction formed in one of the lateral guides, a corresponding cut away portion in the opposite lateral guide, a star wheel for engaging the body portion of each 25 article and forcing it forward past said offset or obstruction with the head of the article in turning engagement therewith, and means for driving said star wheel at a higher rate of speed than that at which 30 said stream of articles is normally forced along the guideway.
- 35 4. In a mechanism for turning articles having parallel sided heads and bodies of less diameter than the heads, a guideway comprising base guides adapted to engage the under sides of the heads of the articles with the bodies thereof depending between them and lateral guides for engaging parallel sides of the heads of the articles, means 40 for feeding a continuous stream of the articles along said guideway by pressure from the rear, in combination with means for turning said articles, comprising an offset or obstruction formed in one of the lateral 45 guides, a corresponding cut away portion in the opposite lateral guide, a star wheel for engaging the body portions of each article and forcing it forward past said offset or obstruction with the head of the 50 article in turning engagement therewith, and means for driving said star wheel at a higher rate of speed than that at which 55 said stream of articles is normally forced along the guideway, said means comprising a star wheel projecting into the path of and 60 actuated by the moving stream of articles and a driving connection therefrom to said first mentioned star wheel.

65 actuated by the body portions of the articles as they are forced forward along said guideway, and a driving connection therefrom to said first mentioned wheel.

5. In a mechanism for turning articles 70 having parallel sided heads and body portions of less diameter than the heads, a guideway comprising base guides adapted to engage the under sides of the heads of the articles with the bodies thereof depending between them and lateral guides for engaging parallel sides of the heads of the articles, means for feeding a continuous stream of the articles along said guideway by pressure from the rear, in combination 75 with means for turning said articles, comprising an offset or obstruction formed in one of the lateral guides, a corresponding cut away portion in the opposite lateral guide, a star wheel for engaging the articles 80 and forcing them forward past said offset or obstruction in turning engagement therewith and means for driving said star wheel at a higher rate of speed than that at which 85 said stream of articles is normally forced along the guideway.

6. In a mechanism for turning articles having parallel sided heads and body portions of less diameter than the heads, a guideway comprising base guides adapted to engage the under sides of the heads of the articles with the bodies thereof depending between them and lateral guides for engaging parallel sides of the heads of the articles, means for feeding a continuous 90 stream of the articles along said guideway by pressure from the rear, in combination with means for turning said articles, comprising an offset or obstruction formed in one of the lateral guides, a corresponding 95 cut away portion in the opposite lateral guide, a star wheel for engaging the articles and forcing them forward past said offset or obstruction in turning engagement therewith and means for driving said star wheel at a higher rate of speed than that at which 100 said stream of articles is normally forced along the guideway, said means comprising a star wheel projecting into the path of and 105 actuated by the moving stream of articles and a driving connection therefrom to said first mentioned star wheel.

7. In a machine of the class described, a guideway, means for forcing a continuous stream of articles along said guideway by 110 pressure from the rear, in combination with means for accelerating the forward movement of one of the articles in the guideway to space it apart from the preceding article of the stream, said mechanism comprising 115 a rotor adapted to be rotated by the forward movement of said articles and a second rotor adapted to force forward in the guideway articles delivered from said first mentioned 120 rotor; and power transmitting connections 125 130 135 140 145 150 155 160 165 170 175 180 185 190 195 198 199 200

between said rotors adapted to drive the second rotor at a higher peripheral speed than said first mentioned rotor.

8. In a machine of the class described, a guideway, means for forcing a continuous stream of bolts along said guideway by pressure from the rear, in combination with mechanism for accelerating the forward movement of one of the bolts in the guideway to space it apart from the preceding bolt of the stream, said mechanism comprising a star wheel projecting into the path of the bolts and adapted to be driven by the forward movement thereof and a second star wheel projecting into said guideway in operative relation to register with and feed forward the bolts as disengaged from said driven wheel, and gearing between said wheels whereby said bolt feeding wheel is rotated by said bolt driven wheel at a peripheral speed greater than that of said bolt driven wheel.

9. In a machine for trimming the parallel sides of square headed bolts, a guideway having slotted bottom guides for supporting the bolts by the heads with their bodies depending through the slot and lateral guides adapted to engage parallel sides of the head, two successive sets of rotary trimming shears spaced apart along said guideway, each set arranged to trim simultaneously the opposite parallel sides of the same bolt head and to force a continuous stream of bolts along said guideway by pressure from the rear, in combination with a mechanism for accelerating the forward movement of one of the bolts in the guideway to space it apart from the preceding bolt and for giving it a quarter turn on its longitudinal axis, said spacing and turning mechanism comprising an offset or obstruction formed in one of the lateral guides, a yielding presser-foot arranged in the opposite lateral guide, a star wheel projecting in the path of the bodies of the bolts in advance of said obstruction and adapted to be driven by the forward movement of said stream of bolts, and a second star wheel projecting into the path of the bolt bodies in operative relation to register with the body of each bolt as it becomes disengaged from said driven wheel and thereby to feed the bolt forward past said offset or obstruction with one corner of its squared head in turning engagement therewith, and gearing between said wheels whereby said feeding wheel is rotated by said bolt driven wheel at a peripheral speed greater than that of said bolt driven wheel.

10. In a machine for trimming the parallel sides of square articles, a guideway having bottom guides for supporting the articles and lateral guides adapted to engage their parallel sides, and successive sets of rotary trimmers along said guideway arranged in pairs so as to operate simulta-

neously on opposite sides of successive articles and rotated in a direction to force a continuous stream of the articles along said guideway by pressure from the rear, in combination with means between said sets of trimmers for giving said articles a quarter turn about their axes, said means comprising an offset or obstruction formed in one of the lateral guides, a corresponding cut away portion in the opposite lateral guide, 75 a star wheel for engaging each article and forcing it forward past said offset or obstruction with one corner in turning engagement therewith and means for driving said star wheel at a peripheral speed higher than 80 the speed at which said stream of articles is normally forced along the guideway.

11. In a mechanism for turning articles having parallel sides, a guideway comprising base guides and lateral guides for engaging parallel sides of the articles, means for feeding a continuous stream of the articles along said guideway by pressure from the rear, in combination with means for turning said articles, comprising an offset 90 or obstruction formed in one of the lateral guides, a corresponding cut away portion in the opposite lateral guide, a star wheel for engaging the body portions of each article and forcing it forward past said offset or 95 obstruction in turning engagement therewith, and means for driving said star wheel at a higher rate of speed than that at which said stream of articles is normally forced along the guideway. 100

12. In a mechanism for turning articles having parallel sides, a guideway comprising a base and lateral guides for engaging parallel sides of the articles, means for feeding a continuous stream of the articles 105 along said guideway by pressure from the rear, in combination with means for turning said articles, comprising an offset or obstruction formed in one of the lateral guides, a corresponding cut away portion in the 110 opposite lateral guide, a star wheel for engaging the articles and forcing them forward past said offset or obstruction in turning engagement therewith and means for driving said star wheel at a higher rate of 115 speed than that at which said stream of articles is normally forced along the guideway, said means comprising a star wheel projecting into the path of and actuated by the moving stream of articles and a driving connection therefrom to said first mentioned star wheel. 120

13. In a machine for trimming the parallel sides of square articles, a guideway having lateral guides adapted to engage parallel 125 sides of the articles, two successive sets of rotary trimming shears spaced apart along said guideway, each set arranged to trim simultaneously the opposite parallel sides of the same articles and to force them in a 130

- continuous stream along said guideway by pressure from the rear, in combination with a mechanism for accelerating the forward movement of one of the articles in the guideway to space it apart from the preceding article and for giving it a quarter turn, said spacing and turning mechanism comprising an offset or obstruction formed in one of the lateral guides, a yielding presser-foot arranged in the opposite lateral guide, a star wheel projecting in the path of the articles in advance of said obstruction and adapted to be driven by the forward movement of said stream of articles, and a second star wheel projecting into the path of the articles in operative relation to register with each article as it becomes disengaged from said driven wheel and thereby to feed the article forward past said offset or obstruction with one corner in turning engagement therewith, and gearing between said wheels whereby said feeding wheel is rotated by said driven wheel at a peripheral speed greater than that of said driven wheel.
14. In a machine for trimming the parallel sides of square articles, a guideway having lateral guides adapted to engage parallel sides of the articles, two successive sets of rotary trimming shears spaced apart along said guideway, each set arranged to trim simultaneously the opposite parallel sides of the same articles and to force them in a continuous stream along said guideway by pressure from the rear, in combination with an automatic mechanism for accelerating the forward movement of one of the articles in the guideway to space it apart from the preceding article and for giving it a quarter turn.
15. In a machine for trimming the parallel sides of square articles, a guideway
- having lateral guides adapted to engage parallel sides of the articles, two successive sets of rotary trimming shears spaced apart along said guideway, each set arranged to trim simultaneously the opposite parallel sides of the same articles and to force them in a continuous stream along said guideway by pressure from the rear, in combination with a mechanism operated by movement of the articles for accelerating the forward movement of one of the articles in the guideway to space it apart from the preceding article and for giving it a quarter turn.
16. In a metal working machine, spaced apart means for performing successive operations on metal articles having flat surfaces and corners, in combination with an intermediate guideway for guiding and turning said articles to present them to the second operating means for working at a different angle from the first means, said guideway comprising portions narrow enough to prevent turning of the article and, in alignment therewith, an intermediate portion wide enough to permit turning, said intermediate portion having a stationary detent element arranged in the path of a corner of the forwardly sliding article, whereby the forward movement of the article turns an adjacent flat surface into contact with the guide, a narrow portion of the guideway being located just beyond said turning element to prevent further turning of the article as it slides forward to the second means for operating thereon.

Signed at North Tonawanda, in the county of Niagara and State of New York, this 23rd day of April, A. D. 1917.

GEORGE F. BLASIER.
